2 Claims. (Cl. 317—200)

The invention relates to a deflection coil system for use in television display tubes comprising a screening cap, surrounding the coils, and made of insulating molding material, supporting permanent magnets for image correction.

In known devices of the kind set forth use may be made of rod-shaped correction magnets, which are fastened onto the screening cap in such way that the position of a magnet with respect to the deflection coil system may be adjusted. The invention has for its object to provide a device of the kind referred to above, in which no separate magnets to be adjustably fastened to the cap are needed, so that it may be inexpensive.

In accordance with the invention this is achieved by making the cap at least partly from molding material including permanently magnetizable material. Certain parts of the cap may be magnetized by means of a suitable electro-magnet and are thus capable of fulfilling the function of correction magnets.

The invention will be described more fully with reference to the accompanying drawing in which:

FIG. 1 shows a deflection coil system in a perspective view from the rear of known construction, in which the invention can be carried out;

FIG. 2 shows the deflection coil system of the invention.

The drawings show an essentially truncated-cone-shaped, hood of synthetic resin open at both ends, in which a deflection coil system of known structure (for the sake of clarity this is not shown) for the deflection of the electron beam in a television display tube is arranged. In the known device of FIG. 1 the front end of the hood 1, i.e. the end facing the image screen of the display tube (not shown) from behind has arranged in its neighborhood a number of rod-shaped correction magnets 3 and two cylindrical, rotatable magnets 7, provided with pole shoes 5. In accordance with the invention one or more of these magnets may be replaced by annular zone 9 near the edge of the hood 1, in which zone the hood is made

2

of molded material which contains permanent-magnetizable material i.e. particles having a high coercive force, for example ceramic material such as barium ferrite, preferably in the form of a powdery filler. Discrete parts of this annulus, the location of which approximately correspond to those of some of the magnets 3, can be magnetized by means of a suitable electro-magnet by arranging the poles thereof on the said zone and passing through the magnet a strong current pulse. The parts thus magnetized can fulfill the function of correction magnets. The location of the magnetized zones as shown in FIG. 2 may be determined experimentally by observing their correcting effect on the image; if necessary, the magnetizations may be erased and be replaced by magnetizations at other places and so on, until the desired correction of the raster appearing on the display tube is obtained. Owing to the possibility of varying the magnetization of the annulus 9 no magnets need be employed which have to be fastened to the screening hood 1 so as to be mechanically adjustably, so that the structure may be made inexpensively.

What is claimed is:

1. In a deflection coil system for television display tubes, a screening hood of insulating molding material, said screening hood comprising a generally truncated conical portion for housing deflection coils and an annular marginal portion, said annular marginal portion having a dispersion of permanent magnetizable powder of high coercive force whereby discrete areas of said annular portion may be permanently magnetized for image correction.

2. A deflection coil system for television display tubes, a screening hood of insulating molding material, said screening hood comprising a generally truncated conical portion for housing a deflection coil and an annular marginal portion, said annular marginal portion containing a filler of powdered permanently magnetizable material of barium ferrite whereby discrete areas of said annular portion may be permanently magnetized for image correction.
